KNITTING MACHINE

Rheubin L. Bunton, Hickory, N. C., assignor to
George W. Grove, Hickory, N. C.

Original application June 21, 1937, Serial No.
149,539. Divided and this application April 15,
1939, Serial No. 268,099

4 Claims. (Cl. 66—41)

This invention relates generally to a machine for producing anti-ravel mock-ribbed top seamless hosiery, and more particularly to a circular knitting machine for this purpose.

5 One object is to provide a circular knitting machine for making mock-ribbed stockings. Another object is to produce a circular knitting machine for making mock ribbed-top stockings from top to toe.

10 A further object is to improve the present circular knitting machines to adapt them to this purpose. Yet a further object is to improve a circular knitting machine to knit a mock ribbed-top stocking from top to toe, starting with bare needles and at the top.

15 A further object is to arrange the machine to knit the top with a laid-in first anti-ravel course, and with the next course knitted to it and to succeeding courses.

20 Still another object of this invention is to provide a machine for knitting the first and second top courses of a mock-ribbed top hosiery with elastic yarn.

25 Other objects and advantages of this invention will appear from the following description taken in connection with the accompanying drawings.

In the accompanying drawings wherein like reference characters indicate corresponding parts in various figures,

30 Figure 1 is a fragmentary perspective of a circular knitting machine, incorporating features of the present inventive concept.

Figure 2 is a development of part of the knitting wave and cams of a Scott and Williams revolving needle cylinder circular knitting machine, including features of the present invention.

35 Figure 3 is a fragmentary side elevation from the right in Fig. 1 showing the mechanism for feeding and for clamping and cutting an elastic 40 yarn used to form the first two courses of mock ribbed-top hosiery, and

45 Figure 4 is a diagram to illustrate the formation of the top of a stocking in accordance with the features of this invention.

Considering the drawings in greater detail, a preferred embodiment of the invention is illustrated and described.

In carrying out this invention, new machines will have included therein the features of this inventive concept and a pre-existing knitting machine will be modified by providing the needle bank with jacks arranged under alternate needles in two sets, the jacks of one set being of a predetermined length and the jacks of the other set being of a different predetermined length and ar-

ranged in alternation with the jacks of the first named set, means being also provided for raising said jacks in succession, so that the needles raised by one set of jacks will be positioned at a predetermined height to receive fed yarn in the hooks thereof only during the first round of knitting, and the needles raised by the other set will be positioned at a lower predetermined height to receive the yarn in the hooks thereof during the second round of knitting while casting off the 10 yarn fed on the first round.

Thus, in the drawings a standard Scott & Williams circular knitting machine is shown converted to the needs of this invention. The needles 12, in the upper row or set of the needle bank 10 15 are raised by jacks 14 of a predetermined length, while needles 16 in the intermediate row or set are raised by shorter jacks 18. Jacks are not used with the remaining or lowermost row of needles 20.

20 The stocking which is made by the improved circular knitting machine is shown in part and in a greatly enlarged scale in Fig. 4. It comprises a mock ribbed-top 22 with a leg portion 24. The former has a single ply welt, that is, it is of a 25 single thickness. The stocking or half-hose is knitted from top to toe starting with the bare needles on one machine. The mock ribbed-top is connected by a transfer 26 to the leg.

25 The first two courses 28 and 30 are preferably 30 formed of covered rubber yarn. Upon the completion of the second course the elastic yarn is clamped and severed, and the knitting continued with plain yarn. The mock ribbed-top 22 is 35 knitted by the two upper rows of needles 12 and 16. During the knitting of this top the lower needles 20 are depressed by a special sliding cam 32, so they will pass under the usual stitch cams 34 and 36 without being affected thereby.

35 The transfer from the top 22 to the leg 24 is 40 effected by sliding the cam 32 out of the path of the butts 38 of the needles 20, thereby leaving all the needles in position for operation by the stitch and draw down cams in the usual manner. The top and bottom center cams 40 and 42 operate in 45 the customary desired manner, with the cam cylinder or ring 44, and the jack cam 46.

In the sequence of knitting contemplated by this invention the elastic yarn 48 is moved by an adjustable yarn feed 50 into the position of 50 Fig. 2, where the yarn is laid in the hooks of the uppermost needles 12. The thread is thus caught by every fourth needle 12 of the complete needle bank. Since the needle bank is cylindrical, the thread 48 between adjacent needles of the top 55

row or set forms chords to the circle of the complete cylinder of needles. As the intermediate needles 16 are raised under the action of the stitch cams 34-36, these chords of yarn pass behind the 5 intermediate row of needles 16.

Upon completion of the first elastic course 28, the elastic yarn feed 50 drops to the level of the intermediate row 16, so that all the needles in both rows 12 and 16 may catch the thread. The 10 second elastic course 30 is knit, using every other needle of the entire needle bank. The elastic yarn is then held and severed by the clamping mechanism designated generally by the reference numeral 52; and the inelastic yarn 54 fed 15 to the machine.

The clamping mechanism comprises the clamping head operated by lever arm 56 which in turn is operated by the link 58. This link connects with the upper end 60 of bell crank 62 the latter being operated by a push rod 64 from the cam cylinder 66 associated with the main cam cylinder of the machine. Adjustment can be obtained by the collar and set screw 68. The yarn feed 50 is adjustably secured at 70 in the bell 25 crank 72. The latter is pivoted upon a shaft 74 and retained by the collar 76. The bell crank is biased by the spring 78 and is moved by the push rod 80 acting on cam 82 carried in the bell crank. The push rod is moved by the cam 84 associated 30 with the main cam drum. The yarn feed is shown in an intermediate full line position in Fig. 2 as well as in dotted lines for a clear upper point and a lower intermediate position. The bell crank 72 and the lever 56 are tied by a spring 86.

35 The knitting of the mock ribbed-top is continued, by operation of the two upper rows of needles, through the desired number of courses. Then the transfer is effected automatically by removal of the slide 32 from the path of the 40 lowest row. All the needles of the entire needle bank then operate to complete the leg 24 of the stocking.

The novelty of this invention has to do more particularly with the use of the two sets of jacks 45 of different lengths to raise alternate needles of the entire needle bank in two sets to different predetermined heights above the remaining needles, while the latter are removed by a slide cam from operative contact with the stitching cams. This 50 construction renders it possible to knit mechanically on a single machine a complete mock

ribbed-top stocking starting with the bare needles and knitting through the transfer from top to toe.

This application is a division of my pending application, Serial Number 149,539, filed June 21, 5 1937.

Although a preferred embodiment of the invention is shown and described, variations within the true spirit and scope of the same are to be determined from the appended claims. 10

What I claim is:

1. In a circular knitting machine, a needle bank, two sets of jacks arranged under alternate needles of the needle bank, the jacks of one set being of a predetermined length and the remaining jacks being of a different predetermined length and arranged in alternation with the jacks of the other set, and means for raising said jacks in succession, so that every other alternate needle is raised to a predetermined height to receive a 20 yarn fed to the hooks thereof only on the first round of knitting and the remaining alternate needles are raised to a different predetermined height to receive the yarn in the hooks thereof on the second round of knitting while casting off 25 the yarn fed on the first round. 15

2. The combination of the machine set forth in claim 1 with means movable into and out of operable position to by-pass the remaining needles of the needle bank around the stitch cams 30 of the machine.

3. In a circular knitting machine having a needle bank and stitch cams, two sets of jacks arranged under alternate needles in said needle bank, the jacks of one set being of a predetermined length and the remaining jacks being of a different predetermined length and arranged in alternation with the jacks of the other set, means for raising said jacks in succession to position said alternate needles in two sets at heights determined by said jacks and for operation by said stitch cams, and yarn feeding means movable to two different positions, in one of which it feeds yarn to the highest set of needles only, and in the other of which it feeds yarn to both of said sets 45 of needles. 35

4. The machine set forth in claim 3 in combination with means for by-passing the remaining needles of the bank around said stitch cams. 40
